ELECTRICAL CONNECTOR

Edward J. Allen, Cleveland, Ohio, assignor to The
Leece-Neville Company, Cleveland, Ohio, a cor-
poration of Ohio

Application January 10, 1945, Serial No. 572,137

2 Claims. (Cl. 173—328)

1

This invention relates to detachable or separable electrical connectors of the type embodying a plurality of contacts and aims to provide an improved device of this kind, wherein the cooperating contacts are carried by telescoping housing members and serve as a means for releasably connecting the housing members with each other.

Another object of this invention is to provide an improved connector of this character, in which the cooperating contacts have locking elements thereon adapted to be engaged or disengaged by relative rotary movement between the housing members.

A further object of the present invention is to provide an improved connector of this kind, embodying resilient means for maintaining a desired pressure on the contacts and which resilient means is substantially unaffected by the electric current or by thermal conditions existing in or adjacent the device.

Other objects and advantages of the invention will be apparent from the following description when taken in conjunction with the accompanying sheet of drawings wherein:

Fig. 1 is a top plan view of a connector constructed according to the present invention;

Fig. 2 is a side elevation of the device;

Fig. 3 is a bottom plan view thereof;

Fig. 4 is a longitudinal sectional view taken through the device substantially as indicated by line 4—4 of Fig. 1;

Fig. 5 is a perspective view showing the device partly in section and with the housing members separated from each other;

Fig. 6 is a perspective view showing one of the female contact members in detached relation; and

Fig. 7 is a partial longitudinal sectional view similar to Fig. 4 but showing a modified construction.

As shown in the embodiments illustrated in the accompanying drawing, the improved electrical connector of the present invention comprises, in general, a pair of telescoping relatively rotatable male and female housing members 10 and 11, and cooperating male and female contact members 12 and 13 carried by the respective male and female housing members. The housing members can be provided with any desirable number of the contact members 12 and 13, and in this instance, the housing member 10 carries three of the male contact members 12a, 12b and 12c, and the housing member 11 carries three of the female contact members 13a, 13b, and 13c.

2

Before proceeding further with the detailed description, it should be pointed out that the improved connector can be used for various purposes and in connection with different kinds of electrical devices and equipment. It is especially suitable, however, for use with certain types of generators, and in Fig. 2 the connector is shown with the housing member 11 thereof mounted on a structure 15 which may be a part 5 of the particular electrical apparatus with which the connector is being used, and for example, may be a portion of the housing or frame of a generator.

The male housing member 10 may be molded, 15 or otherwise formed, from suitable material which is of an electrically insulating character and which also has adequate strength and low thermal conductivity. This male housing member includes an axially extending substantially cylindrical plug portion 16 which carries the male contact members 12a, 12b and 12c. The male housing member 10 may also include an outer sleeve or skirt portion 17 which surrounds the plug portion 16 with an annular space or recess 18 therebetween. This annular space accommodates a resilient member or washer 19 which serves both as a spring and packing as will be further explained hereinafter. A second washer 20, formed of fibre or other relatively 20 tough or hard material is preferably also provided in the annular space 18 in overlying or covering relation to the washer 19.

The male contact members 12 are constructed with threaded stems 21 which are disposed in 25 spaced relation to each other and extend axially through the plug portion 16. These stems can be either molded into the material constituting the housing member 10 or can be accommodated by suitable preformed openings provided in the plug portion. The lower ends of the male contact members 12 are provided with integral lateral locking elements or fingers 22 which extend substantially radially outwardly of the plug portion 16 and are seated in preformed recesses 23 provided in the lower end of the plug portion and which recesses hold the fingers against rotating or rocking about the axes of the stems 21. The fingers 22 are of a length such that they project beyond the cylindrical surface of the plug portion 16 for locking cooperation with the female contact members 13, as will be explained hereinafter. The threaded stems 21 are provided with suitable clamping nuts 25 which serve to retain the contact members in assembled position in the housing member 10 and also facilitate

tate the attachment of electrical conducts to the stems of these contact members.

The female housing member 11 is also molded, or otherwise formed, from insulating material having a low thermal conductivity and comprises a plate portion or base 27 and an axial sleeve portion 28 formed integral with the base. The base 27 is here shown as being quadrangular in shape and having openings 29 therein by which the female housing member can be attached to the structure 15, as shown in Fig. 2, by means of appropriate screws 30. The cylindrical sleeve portion 28 is of a size to enter the cylindrical sleeve portion 17 of the housing member 10 and has limited relatively rotary movement therein. The sleeve portion 28 houses the female contact members 13a, 13b and 13c which are disposed therein in an annular series which receives and accommodates the plug portion 16 of the male housing member 10.

As shown in the drawings, the female contact members 13 each comprise a flat segmental base or plate 32 and a curved axially extending plate or sleeve segment 33. The sleeve segments 33 have a curvature enabling the same to lie against, and conform to, the curved inner face of the sleeve 28 of the female housing member 11. At or adjacent the junction of the sleeve segments 33 with the bases 32, each of the female contact members is provided with an arcuately extending slot 34 of an axial width sufficient to permit the entry of the fingers 22 of the male contact members 12. The slots 34 preferably include axially extending locking recesses 35 in which the fingers 22 have seating engagement when the housing members 10 and 11 have been fully connected or engaged with each other.

As best seen in Fig. 5, the female contact members 13 are disposed in circumferentially spaced relation around the socket or recess of the sleeve portion 28, and the spacing of the sleeve segments 33 provides therebetween three axially extending slots or passages 36 of a width to receive the locking fingers 22 of the male contact members 12 when the housing members 10 and 11 are brought into telescoping relation with each other. The bases 32 of the female contact members 13 are likewise disposed in spaced relation and are preferably provided with threaded openings 37 for the reception of screws 38 which extend through the base 27 of the female housing member 11 for retaining the female contact members in the above described relation in the sleeve portion 28. The bases of the female contact members are also provided with relatively larger openings 39 in which the stems 40 of the headed element 41 are received and brazed or otherwise secured. The stems 40 extend through the base 27 of the female housing member and assist in holding the female contact members in proper position and the heads of these elements lie outside of or below the base 27 so that wires or other suitable electrical conductors can be readily connected therewith.

From the construction and relative arrangement above described for the cooperating housing members and contacts, it will be seen that by relative axial movement between the housing members, the locking fingers 22 of the male contacts 12 can be moved axially into the passages 36 whereupon the plug portion 16 of the male housing member enters the sleeve portion 28 of the female housing member and the sleeve portion 17 of the male housing member slidably moves over the sleeve portion 28. By applying

axial pressure to the two housing members, the end of the sleeve portion 28 can be made to engage the washer 20 and compress or deflect the underlying resilient washer or spring 19. While this axial pressure is being maintained, the housing member 10 is rotated relative to the housing member 11, in a clockwise direction as seen in Fig. 5, to cause the fingers 22 to enter the arcuate slots 34 of the female contact members. When the fingers 22 have been rotated to a point substantially in register with the locking recesses 35, the axial pressure is released to permit the fingers to seat in these locking recesses which thereupon hold the housing members against accidental relative rotation in the reverse direction. The expansive action of the resilient washer or spring 19 retains the fingers 22 in the locking recesses 35 and also causes the fingers 22 to be pressed against the female contact members with an appropriate or desired degree of pressure for obtaining a good electrical connection therebetween. As shown in the drawing the curved contact members 13 are of substantially the same axial length as the sleeve portion 28 and form a cylindrical lining therein in which the plug portion 16 is axially and arcuately slideable while the housing members are being connected together or disconnected. The sleeve portion 17 of the housing member 10 is also axially and arcuately slideable around the sleeve portion 28 of the housing member 11 so as to form a tight enclosure for the contact members.

In Figs. 1 to 5, inclusive, the resilient member 19 is shown in the form of a washer made of yieldable material such as soft rubber or sponge rubber. When this member is subjected to axial pressure, as explained above, it forms a packing or seal in the annular recess 18 which prevents water or other fluid from entering the device and coming into engagement with the contacts therein. Instead of this rubber washer, a metal spring 43 can be used, as shown in Fig. 7. The spring 43 is made from a flat strip and is in the form of a ring or washer having a wavy or corrugated configuration which renders the same resilient and pliable.

It is usually desirable that the housing members 10 and 11 be capable of telescoping engagement in one relative position only, so that the male contact members will engage the proper respective female contact members. This can be accomplished as by providing an axial rib or lug 45 on the outer surface of the sleeve 28 and an axial slot or recess 46 on the inner surface of the sleeve 17. The recess 46 receives the rib 45 when the housing members 10 and 11 are brought into proper telescoping relation and permits sufficient relative rotary movement between housing members to engage the fingers 22 in the locking recesses 35 of the female contact members 13.

From the foregoing description and the accompanying drawing it will now be readily understood that the present invention provides an improved electrical connector of a simple and compact character which can be economically produced and which is strong and durable and will render very satisfactory service. It will be seen, moreover, that the male and female contact members of the device cooperate in a manner to provide a good electrical connection and also serve as a bayonet locking means for releasably holding the housing members in connected relation. Additionally, it will be seen that the resilient means embodied in the device for maintaining the desired pressure between the

contact members is uneffected by either the electric current or by thermal conditions existing in or adjacent the device.

While I have illustrated and described my improved electrical connector in considerable detail, it will be understood of course that I do not wish to be correspondingly limited but regard my invention as including all changes and modifications coming within the scope of the appended claims.

Having thus described my invention, I claim:

1. An electrical connector comprising a housing member having a hollow cylindrical portion, a second housing member having a cylindrical plug portion adapted for relative rotary telescoping engagement in the hollow cylindrical portion of the first housing member, a group of contacts mounted in the first housing member and having curved portions disposed in spaced relation in an annular series adjacent the wall of said hollow cylindrical portion and forming a cylindrical lining therein, said curved portions having slots formed therein and which include substantially axially extending locking recesses, contacts carried by the plug portion of said second housing member and having locking projections engageable in said slots and adapted to seat in said locking recesses, and resilient means between said housing members and tending to cause axial separation thereof for holding said projections in said locking recesses, said plug portion being axially and arcuately slidable in said cylindrical lining during said relative rotary telescoping engagement, said second housing member also having a sleeve portion extending coaxially around said plug portion and spaced therefrom and being arcuately and axially slideable around the hollow cylindrical portion of said first housing member during said relative rotary telescoping engagement.

2. A connector of the character described com-

prising a housing member having a substantially cylindrical sleeve portion and a plug portion disposed substantially coaxially of said sleeve portion and separated therefrom by an annular space, a second housing member having a substantially cylindrical sleeve portion adapted to telescope into the sleeve portion and annular space of the first housing member, a group of contacts located inside the sleeve portion of the second housing member and having curved portions disposed in spaced relation in an annular series and lying adjacent the wall of the last mentioned sleeve portion and conforming substantially to the curvature thereof, said curved portions having slots therein which include substantially axially extending locking recesses, a group of contacts carried by the first housing member and having stem portions extending through the plug portion thereof, projections on said stem portions and engageable in said slots and adapted to seat in said locking recesses, and annular resilient means located in said annular space and adapted to be flexed during assembly of said housing members.
